VAPOR CONSERVING TANK

James O. Jackson, Crafton, Pa., assignor to Pittsburgh-Des Moines Company, Pittsburgh, Pa., a corporation of Pennsylvania

Application January 31, 1942, Serial No. 429,050

6 Claims. (CL. 220—85)

1

This invention relates to tanks for the storage of volatile liquids and more particularly to tanks having roofs expandable under increases in vapor pressure.

Many liquids, such as commercial gasoline, have a vapor pressure when confined in a gas-tight storage tank. It is usually not economical to design such tanks with sufficient strength to resist such internal vapor pressure and to avoid the danger of failure of the tank it is common practice to place a vent usually in the tank roof so that the vapor may freely vent without causing increased pressure on the underneath side of the tank roof. This results in a substantial waste.

It has been found that if tank roofs are made flexible so that they may become expanded or inflated by the increasing volume of the liquid vapor the pressure on the tank roof may be kept within safe limits and with such construction it is only necessary to vent the tank when the inflatable roof has expanded or deflated to its safe limits. The economy of such a tank is based upon the fact that the generation of vapor from the liquid requires an appreciable amount of time for it is necessary for the tank contents to slowly absorb heat from the sun's rays or the outside atmosphere in order to permit such vaporization to continue. It would, therefore, be most desirable to provide a storage space for the tank vapors which would approximately equal the volume of vapor at a safe pressure generated during the warm daylight hours which vapors in the cooler night hours would condense to a liquid allowing the roof to deflate to its original position. This cycle would then be repeated from day to day with theoretically no loss of tank contents.

Inflatable roofs as heretofore devised have many objectionable features and frequently fail to function as intended. Roofs made of sheet metal which expand from a central position to an expanded position must depend for their operation on the sheet metal buckling as it collapses, such buckling frequently causing sharp bends, kinks, and fatigue failure of the metal. Other types work on the principle of a reversal of shape. This type has the serious objection that due to the inherent resistance of a portion of a conical or spherical surface considerable pressure may be built up before the roof reverses and when reversal does occur under these conditions the shock or impact over a relatively large area may cause failure of the surfaces through rupture and when this occurs fire frequently results from sparks struck by the sliding surfaces.

It is the primary object of my invention to

2

provide an improved inflatable or vapor conserving roof of novel construction which is substantially free of the above objections.

Another object of my invention is to provide an inflatable roof of the reversing type in which the reversing action is controlled so that it will proceed smoothly as the roof inflates and deflates.

Another object of my invention is to provide a construction in which the bending of the sheet metal at the critical point is spread out over a relatively large area and, therefore, reduced in intensity.

Still another object of my invention is to provide a vapor conserving roof which will reduce the vapor space to as small a volume as possible, with sufficient flexibility and control to reduce the venting losses therefrom to an economical minimum.

A still further object of my invention is to provide a roof which can be very economically built from steel sheets which need not be pressed or formed for if, as contemplated by my invention, the roof is laid out and built upon the structural supports devised by me to support it in its deflated position it will, from the inherent geometry, fit exactly in the expanded position.

To these ends I provide a flexible roof which in the down or deflated position rests on circular rafters set at different elevations to produce a predetermined double curvature, designed to permit the roof to flex smoothly from the deflated to the inflated position. The theoretical area of the roof plating being equal in the deflated and inflated position there is no tendency for buckling in these positions. In passing through the intermediate positions the roof sheets are subjected to a nominal radial compression which is kept within conservative limits. Due to the fact that the curvature of the exterior portion of the roof is reversed from that of the interior portion, when the roof is in its deflated position, there is set up in the metal a bending stress which causes the roof to expand smoothly from the outside towards the center as the vapor volume increases and to collapse smoothly from the center to the outside as the vapor volume decreases. This roof shape avoids difficulties which have been experienced with roofs of conical or truncated conical shape. This feature is important because unless the roof action is smooth excessive pressure is apt to be built up which may cause the roof to expand or collapse very suddenly, causing shock failure with a possibility of fire or explosion.

Another advantage inherent in my design is that the roof plates where they connect to the

rim angle at the top of the tank shell are subjected to practically no bending due to the inflation or deflation of the roof. In the case of roofs using conical or truncated conical roof shapes the angular deflection at the outer edge is considerable and may cause fatigue failure of the metal at this point.

Other advantages in my invention will appear from the detailed description.

In the accompanying drawings, showing for purpose of exemplification, but without limiting my invention or claims thereto, certain preferred embodiments of my invention:

Fig. 1 is a vertical sectional view; showing one form of my tank;

Fig. 2 is a half-plan view with a portion of the roof sheets removed to show the arrangement of the supporting framing;

Fig. 3 is an enlarged sectional view of the upper corner showing more clearly how the roof flexes as it expands, and

Fig. 4 shows another form of the device which provides for larger capacities.

Referring to the drawings, there is shown in Fig. 1 a relatively thin sheet metal roof 4 formed of a plurality of sheets attached together at their edges as by welding. The roof is attached about its periphery to the upper portion of the tank, preferably to the top angle member 5 which in turn is secured to the upper periphery of the cylindrical tank shell 6.

The flexible sheet roof 4 is originally built on the circular rafters 7, 8, 9, 10, 11 and 12 which in turn are supported by girders 13 and 14. In order to give the desired curvature to the roof when in deflated condition, while maintaining standard size of the rafters, the rafters 7, 8 and 9 are preferably provided with intermediate supports 7', 8' and 9', respectively, connecting them to said girders. By this construction the roof is divided into a central circular portion concaved downwardly and an outer annular portion concaved upwardly. Each girder 13 is conveniently supported at its outer end by attachment to tank shell 6, as by welding, and at its inner end upon beam 15. Each girder 14 is preferably supported at its inner end on a platform 16' mounted on the top of a column 16 and at its outer end on beam 15 which in turn is supported by columns 17.

A valve 18 attached to a housing 19 surrounding a central opening 20 in the roof sheets is operated by chain 21 which when the roof has expanded to a predetermined safe point opens to relieve any further increase of internal pressure which might cause failure.

Water accumulating in the central portion of the roof when it is in a deflated position is conducted down pipe 22 into the tank. Said pipe at its upper end extends through and is secured to said roof structure as by welding and at its lower end is slidably engaged by the support 23 attached to the column 16.

In Fig. 3 the roof is shown in its initial or deflated position I. The roof sheet 4 is sprung over the rafter 7 and attached to the tank rim angle member 5 by welding or in any other suitable manner so that the roof sheet 4 has an initial bending stress extending from angle member 5 inwardly. When the temperature of the tank contents increases gas pressure is exerted on the entire interior of the tank and on the underneath side of the roof sheets 4. When the internal pressure approaches the weight of the roof sheets per unit of area the roof sheets 75

will flex to position II approximately free of rafter 7 relieving the initial bending stress. When the roof has reached its full expansion it will be in position III. In that position the initial bending stress will be almost entirely relieved except at the outer periphery.

It is, therefore, apparent that due to my novel construction which takes advantage of the elastic property of steel sheets the radius of the initial curve of the roof sheets above rafter 7 will gradually increase and extend inwardly as the tank roof inflates until, when it reaches its full inflated position III the center portion will have risen to a point where no sudden reversal with damaging effects will take place.

Another form of my device is shown in Fig. 4. In this form the roof sheets 4' are flexed over the cylindrical tank shell 6 and extend a considerable distance on the outside of the tank. Roof sheets 4' are, however, not connected to tank shell 6 directly but are connected to annular sheets 24 which in turn are connected to tank shell 6 through reinforcing top angle member 5 to which it is attached as by welding. It is apparent that this construction increases considerably the vapor capacity of the roof not only because of its larger diameter but because of the added capacity obtained by the flexibility of the annularly arranged sheets 24.

While I have shown and described certain preferred embodiments of my invention it is to be understood that it is capable of many modifications and that changes in construction and arrangement may be made therein without departing from the spirit and scope of my invention. I therefore desire to cover in the claims all novelty in my invention over the prior art.

What I claim as new and desire to secure by Letters Patent is:

40. 1. In combination, a tank for volatile liquids and the like, an expandable sheet metal roof attached thereto about its periphery, and annular means for supporting said expandable roof in its lowermost or unexpanded position while maintaining an outer circular zone of said roof for an appreciable distance inside its outer periphery at a height to prevent appreciable angular change between said roof and tank at their line of attachment to each other, said supporting means being adjacent to and spaced radially inwardly from the periphery of the roof intermediate the axis of the tank and its periphery and extending above said periphery to permit the central portion of the roof to be dished to present a convex surface 55 toward the interior of the tank when the roof is deflated.

2. The combination defined by claim 1 in which the roof extends beyond the upper periphery of said tank and is provided with an inwardly extending flexible portion attached at its inner edge to said tank.

3. An inflatable elastic sheet metal storage tank roof having its peripheral portion rigidly attached to said tank; a support therefor disposed around the axis of the tank between said axis and the periphery of the tank and spaced therefrom, and extending above the plane of the attachment of said roof to the periphery of the tank a distance sufficient to cause the portions of said roof on radially opposite sides of said supporting means to have radii of surface curvatures in reverse directions when the tank is deflated, the radius of curvature of the peripheral portion of said roof at all times extending downwardly, 70 said support contacting the underside of said

peripheral portion of the roof when deflated; the mid-portion of said roof in deflated position extending below the peripheral portion.

4. A tank adapted to contain a volatile liquid; an expandible sheet metal roof therefor rigidly attached to said tank at its upper periphery; a support for said roof in its lowermost position when the tank is deflated comprising a series of vertically supported radially spaced coaxially arranged circular girder-like rings the outermost of which has its supporting edge above the upper periphery of said tank and in spaced relation thereto and the inner rings of which have their supporting edges lower than the supporting edge of said outermost ring, progressively toward the tank axis.

5. A tank, adapted to contain a volatile liquid; an expandible sheet metal roof therefor having its peripheral edge rigidly attached to the upper periphery of the tank; a support for said roof when in its lowermost position due to deflation of the tank, comprising a coaxially arranged outer supporting portion having its supporting edge at sufficient height above the upper periphery of the tank and in spaced relation thereto, to contact the outer peripheral portion of the roof inwardly of its periphery to limit the flexure of the portion of said roof adjacent its attachment to the tank during the operation of said roof to prevent plastic deformation, and a coaxially arranged supporting portion spaced inwardly from the outer supporting portion and having its supporting edge lower than the peripheral edge of the roof, the outer peripheral portion of the roof which is contacted by the first mentioned supporting portion having a radius of curvature downwardly at all times.

6. The method of constructing an inflatable sheet metal roof for a storage tank comprising

the steps of providing a series of vertically supported radially spaced coaxially arranged circular girder-like rings, the outermost of said rings being above the plane of the intended roof connection to the tank and spaced therefrom and the inner rings being lower than said outermost ring progressively toward the tank axis; positioning the roof sheets on said rings to form a concave assembly; joining the edges of the roof sheets which are to form the central portion of the roof to each other and to the sheets which are to form the outer portion of the roof, leaving the sheets of the latter unjoined to each other; flexing the free ends of the outside roof sheets over said outermost ring downwardly into contact with the top of the tank, and rigidly joining said ends thereto and the adjacent edges of said outer sheets to each other, whereby said outer portion of the roof is prestressed to a curvature having a downwardly extending radius causing it to expand smoothly and without buckling.
